[57] ABSTRACT

The invention concerns a process for connecting two mutually perpendicular tubes of different diameters by anchoring the end of the smaller tube in a bore in the mantle surface of the larger tube, particularly for connecting rungs and stiles, of a ladder, and a ladder so made. A plug of frusto-conical shape is introduced with its narrower end into the smaller tube the end of which, together with the plug, is pressed through the bore against the inner wall of the thicker tube such that the edge of smaller tube within the bore is deformed against the bore edge by the plug.

TUBE CONNECTION, E. G. FOR A LADDER

The present invention relates to a process for connecting two at least approximately mutually perpendicular tubular pieces with different diameters by anchoring the tube end of the thinner tube piece in a corresponding bore in the mantle surface of the thicker tube piece, particularly for connecting ladder rungs with ladder stiles. The invention also relates to a ladder made by the process.

There are known tube connections, or rather ladders, wherein the stiles are provided with bores in the mantle surface thereof into which bores the rungs are pressed, welded, flanged or riveted. All these processes are intricate, time-consuming and, in many respects, disadvantageous. In welding, stresses arise at the weld locations, whereby a weakening of the construction results. The connections may easily become loose and cracks often arise which can only be detected later and lead to accidents. Great demands are made on those ladders which find use in sewage pits and canals and which are there particularly exposed to corrosion.

It is an aim of the invention to propose to process which permits a simple and very easily achievable connection of tube pieces, which connection is absolutely water-proof, does not loosen but rather remains practically non-detachable.

The proposed process consists in that a plug which widens conically is introduced with its narrow end into the end of the thinner tube and the tube piece end together with the plug are pressed through the bore in the mantle surface of the thicker tube piece against the inner wall of the latter opposite the bore such that the edge of tube piece within the bore is spread out and compressed against the bore edge due to the penetration thereto of the plug, whereby to form a water-proof and non-detachable connection.

Preferably, at the inner wall of the thicker tube piece, at least where it is opposite the bore in the mantle surface, a stop in the form of a web is arranged against which the free end of the plug is pressed. According to a preferred embodiment through the use of additional lateral webs the pressed-in tube end will be particularly well blocked in.

A ladder made by the process has conical plugs pressed into the rung ends, which plugs come to bear against a web which extends along the inner wall of the ladder stile opposite the bores in the mantle surface of the stile which serve for receiving the rungs.

There may also be a plurality of parallel webs present which are arranged and distributed around the periphery of the inner wall of the tube in the region of the mantle bores.

The accompanying drawing illustrate exemplary embodiments of the subject-matter of the invention and show:

FIG. 1 is a horizontal section of a tube connection,

FIG. 2 is the same connection in vertical section along the line I—I of FIG. 1,

FIG. 3 is a horizontal section of a variant of FIG. 1, and

FIG. 4 is a detail view.

FIGS. 1 and 2 show the connection of two mutually perpendicularly extending tube pieces 1 and 2, where one of the tubes 1 has a greater diameter than the other tube 2. The tube 1 is provided with a bore 3 in its mantle surface through which the end of tube 2 is to be in-

roduced and anchored. To this end, a frusto-conical plug 4, e.g. of hard plastics material, is provided the small, possibly ribbed, end 5 of which is introduced into the end of the tube 2. Next, the tube 2 is pressed into the bore 3, whereby the projecting end 6 of the plug 4 comes to bear either directly against the inner wall of the pipe 1 or, as shown in FIG. 1, abuts against a web 7 which is located at the inner wall opposite the bore 3 in the mantle surface of the tube 1. When the tube 2 is pressed in, the frusto-conical plug 4 spreads the edge of the tube 2 apart and compresses it against the edge of the bore so that a waterproof and non-detachable connection is formed. Simultaneously the tube 2 is closed off inside and outside and the penetration of moisture is prevented. Expediently, the rungs made from the tubes 2 are prestressed, whereby an torsional load that may arise is compensated.

FIG. 3 illustrates a further developed exemplary embodiment of the tube connection. The larger tube piece 20 is designated here with 8 and has a bore 9 into which the smaller tube piece 10 is to be set. Serving to anchor the latter, a plug 11 is again used, which is shown in detail in FIG. 4.

This plug 11 is essentially arranged in five sections. 25 An end section 12 is cylindrical and of somewhat smaller cross-section than the internal cross-section of the tube 10 to be secured. This section 12 serves for guiding the plug 11 and holding it tightly when it is engaged into the tube 10. Next a frusto-conical part 13 is present, the smallest cross-section of which corresponds to that of the section 12, while its greatest cross-section exceeds the internal cross-section of the tube 10. This part 13 has the task of widening the end of the tube 10 when the latter is pressed in.

30 A short cylindrical part 14, adjoining the frusto-conical part 13, changes into a wider frusto-conical part 15 which has the task of spreading apart the edge of the tube 10 in the final phase of the pressing-in. Finally, the end part 16 lies with its end face against the inside of the web 17 arranged on the inside of the tube (see FIG. 3).

35 It is furthermore advantageous if additional webs 18 are arranged laterally of and parallel with the web 17, which webs provide additional resistance during the introduction of the tube end 10 to the plug 11 and cause a still better upsetting or compression of the edge of the tube 2. In this way a ladder made of prefabricated elements may very quickly and simply be assembled together, wherein the non-detachable connections between stile and rungs are absolutely waterproof and remain very resistant to external chemical and physical influences. Advantageously the free ends of the tubes 1 or 8 forming the stiles are closed off with closure plates so that the interior of the tubes is protected against corrosion. The webs utilised serve additionally as stabilisers, whereby the bending resistance of the ladders is increased. The weakening of the tubes 1 or 8 due to the bore 3 or 9 is compensated by the webs 7 or 17 and 18 and by the prestressing of the rungs.

40 60 I claim as my invention:

1. A tube connection comprising a first tube, a second tube substantially perpendicular to the first tube, the tubes having different cross-sections, a bore formed in the second tube for receiving the first tube, a connecting member a part of which is received in the open end of the first tube and the remainder of which abuts, directly or indirectly against the inner wall of the sec-

ond tube, wherein the connecting member comprises a first, cylindrical portion, a second, frusto-conical portion, a third, cylindrical portion, a fourth, frusto-conical portion, and a fifth, cylindrical portion, the first portion being of greater diameter than the fifth portion, and the second portion, is of greater maximum diameter than the internal diameter of the first tube to assist in deforming the end of the latter against the edge of the bore in the second tube and the inner wall of the second tube.

2. A tube connection, particularly suitable for connecting ladder rungs with ladder stiles, consisting essentially of:

a first tube which forms the rungs of the ladder;
a second tube having a larger diameter than the first
which forms the rail of the ladder;

a substantially frusto-conical plug having a projecting annular edge, pressed partly into the end of said first tube for each connection;
said first tube receiving a bore of said second tube;
said bore of said second tube receiving said end of said first tube and also said plug;
a plurality of mutually parallel webs which are arranged and distributed along the periphery of the inner wall of said second tube to serve as stops; and,
said end of said first tube being deformed against the edge of the bore by the plug to bear against said stop to thereby press the plug against the inner wall of the second tube.
